UNITED STATES PATENT OFFICE.

SYLVEONUS D. MOSHER, OF STORM KING, NEW YORK.

TUNNEL-HEAD.

1,098,961.

Specification of Letters Patent. Patented June 2, 1914.

Application filed September 19, 1913. Serial No. 790,739.

To all whom it may concern:

Be it known that I, SYLVEONUS D. MOSHER, a citizen of the United States, residing at Storm King, in the county of Dutchess and State of New York, have invented new and useful Improvements in Tunnel-Heads, of which the following is a specification.

The invention relates to an improvement in tunnel heads designed to form a temporary protecting terminal for the tunnel tube, the head being advanced lengthwise the tunnel or excavation as the tube is constructed.

The main object of the present invention is the provision of means to permit tunneling beneath bodies of water without necessitating the usual costly and dangerous protective construction involved in the ordinary methods.

The invention in its preferred form of details will be described in the following specification, reference being had particularly to the accompanying drawings, in which:—

Figure 1 is a diagrammatic view illustrating generally the method employed in the initial preparation for the tunneling. Fig. 2 is a longitudinal sectional view illustrating the improved head and showing a portion of the completed tube in place in the bed of a river. Fig. 3 is a transverse sectional view through the head. Fig. 4 is a sectional view on the line 4—4 of Fig. 2. Fig. 5 is a transverse section through the tunnel in completed condition. Fig. 6 is a sectional view through the head showing a modified form for raising and lowering same.

With particular reference to the accompanying drawings, the improved tunnel head 1 is made up of a plurality of sections 2 appropriately formed and secured together to provide a cylindrical body, the form of the sections being such as to provide a rear open end for the body and the forward pointed or feeding end 3. Within the body approximately adjacent the pointed ends there is provided a transverse partition 4, and a space forward of said partition is provided with a cylindrical longitudinally arranged casing 5 to which entrance is had through a manhole 6 in the partition, the casing 5 forming a weight chamber, for the reception of appropriate weight by which the nose end of the head may be properly held in position on the tunnel foundation. The head proper throughout its length is formed with an inner shell 7 secured to the

sections 2, and admission to the space within the shell is provided through a man-hole 8 formed in said partition at an appropriate point, preferably within that portion of the head forward of the partition. A compressed air pipe 9 opens through the partition 4 for a purpose of admitting air within the shell and to the inner and outer sections of the head proper, whereby the weight of the head through the proper relative adjustment of a quantity of compressed air and weight in the weight chamber may be controlled to insure proper movement of the head under all conditions of the body of water in which the tunnel is being laid. Adjacent the rear open end the inner shell 7 is provided with an inwardly extending ring 10, and in which is arranged packing rings 11, providing a packing for the head on the immediately adjacent sections of the tunnel casing 12. Packing glands 13, made up in sectional formation, are carried by the head on opposite sides of the bearings 11, the glands fitting the casing section 12 in a manner to exclude the water from entrance between said rings and the tunnel casing section.

A metallic shoe 14 underlies the head and conforms throughout its length and breadth to the shape of the head, the shoe forming a bearing element for the head in its movement lengthwise the tunnel and excavation. In rear of the head the shoe is provided with a weight box 15 adapted to receive any suitable weight for holding the rear end of the head in proper position in a tunnel excavation. The forward end of the shoe, which terminates immediately in advance of the pointed end of the nose of the head, is provided with a ring 16 adapted to receive an anchoring connection, whereby the head may be anchored to prevent its lateral displacement by current.

In the construction of the tunnel in accordance with this invention, the first step is dredging the bed in the bottom of the river in a line of the desired tunnel. A proper foundation is laid as a bed in the channel thus formed and it is on this bed that the head described is operated. The tunnel proper is built within the casing, being made of sectional rings, and as each ring is added or built up, the head is advanced by any appropriate means, so that an additional ring may be added. The tunnel is thus gradually completed with the use of the head, it be-

ing understood that the space surrounding the casing of the tunnel is filled in by any appropriate material, as concrete, up to or above the normal bottom of the stream, this filling in being continuously carried on as the head is advanced so that each section of the tunnel casing when free of the support of the head is inclosed within its filling to maintain the proper alignment and solidify the entire structure. This construction provides for not only rapid work but economy in cost and allows the men to work with little or no danger from the caving in of the usual bulk heads which are employed and does not require compressed air which is also a source of danger. This form of tunnel is especially adapted for work under small streams while it may take the place of the usual expensive coffer dam operation.

In Fig. 6 I have shown a modified means wherein guards 17 are provided on each side of the shoe 14 in which guards are mounted runners 18. The runners are connected to the lower ends of jack screws 19 which extend through the head and have threaded cooperation with abutments 20 within the head. By obvious operation of the jack screws the runners will be operated within the guards and correspondingly lower or raise the forward end of shell, thus keeping said head to grade.

What is claimed is:—

1. A tunnel head including a casing open at one end for coöperation with a tunnel section and pointed at the opposite end, a packing carried by the head to engage the tunnel section, and a shoe carried by the head and forming the bearing support therefor on the foundation of the tunnel channel.
2. A tunnel head including a casing open at one end for coöperation with a tunnel section and pointed at the opposite end, a

packing carried by the head to engage the tunnel section, and a shoe carried by the head and forming the bearing support therefor on the foundation of the tunnel channel, said shoe having its forward end formed with an anchoring connection.

3. A tunnel head including a casing open at one end for coöperation with a tunnel section and pointed at the opposite end, a packing carried by the head to engage the tunnel section, a shoe carried by the head and forming the bearing support therefor on the foundation of the tunnel channel, and a weight box carried by the shoe in rear of the open end of the head.

4. A tunnel head including a casing open at one end for coöperation with a tunnel section and pointed at the opposite end, a packing carried by the head to engage the tunnel section, a shoe carried by the head and forming the bearing support therefor on the foundation of the tunnel channel, a partition transverse the head and a weight chamber carried centrally and longitudinally of the head.

5. A tunnel head including a casing open at one end for coöperation with a tunnel section and pointed at the opposite end, a packing carried by the head to engage the tunnel section, a shoe carried by the head and forming the bearing support therefor on the foundation of the tunnel channel, a partition transverse the head, a weight chamber carried centrally and longitudinally of the head, and means for admitting compressed air to that portion of the head in advance of the partition.

In testimony whereof I affix my signature in presence of two witnesses.

SYLVEONUS D. MOSHER.
